ROTARY TYPE CAN OPENER

Robert E. McLean, Fort Benning, Ga.

Application September 3, 1941, Serial No. 409,419

15 Claims. (Cl. 30—9)

This invention relates generally to the class of instruments or tools designed for opening sealed receptacles such as tin cans and the like, and pertains particularly to the type of opener which is designed to remove the head of a tin can completely and leave a smooth unjagged edge.

The present invention has for its principal object to provide an improved rotary type of can opener in which a novel means is provided for effecting the penetration of a cutting blade into the head of the can and for holding the can for rotation with respect to such blade until the head of the can is completely cut out.

Another object of the invention is to provide an improved can opener having as a novel feature thereof a means whereby the penetration of the head of the can by the cutting blade is effected simultaneously with and by the operation of rotating a single driving lever or crank, thereby avoiding the necessity on the part of the user of first manipulating one element of the device for the penetration of the can head by the cutting blade and then switching to and manipulating a second independent element for rotating the can with respect to the cutting blade as is required in can openers of this general type such as are at present in use.

Another object of the present invention is to provide an improved can opener of the rotary type in which there is only one lever or crank arm to be operated to force the cutter through the end of the can, to firmly engage the can in the device, to cut the end out of the can so as to leave no jagged edges and to release the can from the device.

Still another object of the invention is to provide a can opener of the character stated having only a single operating crank or lever, in which the construction is such that a single series of only clock-wise rotation of the operating handle or crank forces the cutter through the end of the can; firmly secures the can in the device and cuts the end from the can, and subsequent counter-clockwise rotation, not exceeding one and one-quarter turns of the same operating handle or crank arm, releases the can from the device and prepares the device for the reception of the next can.

Still another object is to provide an improved can opener of the character stated wherein the operating handle or crank arm is normally suspended straight downward and out of the way when the device is not being used and the crank handle or arm assumes such position without manual operation after having been turned to

position to release the can from the device, from which suspended position it is only necessary to turn the operating handle clockwise to begin the cycle of opening the next can.

Another object of the invention is to provide in a can opener of the character stated an improved mechanism by means of which there is not only produced the action of effecting the penetration of the cutting blade through the can top upon the initial turning of the operating crank or handle which is employed for rotating the can with respect to the cutting blade but wherein the cutting blade is caused to penetrate the head of the can simultaneously with the rotation of the can so that the head is penetrated by the cutting blade with greater ease and more quickly than is possible with cutters of this type where merely a longitudinal movement of the can toward the cutting blade is made to effect such penetration of the blade through the can top.

Still another object of the invention is to provide an improved can opener having the several advantageous and novel features above set forth, which is adapted to be secured to a supporting wall bracket or other suitable supporting means and which operates smoothly and efficiently and which can be economically and strongly constructed so as to remain serviceable and dependable for a long period of time.

The several embodiments of the invention here illustrated will be best understood from a consideration of the following detailed description taken in connection with the accompanying drawings, it being understood, however, that the invention is not to be considered as limited by the specific illustration or description but that such illustration and description constitutes a preferred embodiment of the invention.

In the drawings:

Figure 1 is a view in side elevation of a can opener constructed in accordance with one embodiment of the present invention showing the handle or crank moved through one and one-quarter turns of its operating cycle and showing the can cutting position of the parts, and also a portion of the mounting for the device;

Figure 2 is a view in top plan of the device shown in Figure 1;

Figure 3 is a section on the line 3—3 of Figure 1;

Figure 4 is a section on the line 4—4 of Figure 2;

Figure 5 is a section on the line 5—5 of Figure 1;

Figure 5^a is a fragmentary view in elevation of

the cutter blade and driving wheel, as seen in viewing the device from the front;

Figure 6 is a view in side elevation of a second embodiment of the invention showing the parts in operative position;

Figure 7 is a view in top plan of the same;

Figure 8 is a vertical section on the line 8—8 of Figure 6;

Figure 9 is a vertical section on an enlarged scale on the line 9—9 of Figure 6;

Figure 10 is a sectional view on the line 10—10 of Figure 3;

Figure 11 is a sectional view on the line 11—11 of Figure 3;

Figure 12 is a view in side elevation of a third embodiment of the present invention;

Figure 13 is a view in elevation of the can side of the opener shown in Figure 12, or the side opposite from that shown in Figure 12;

Figure 14 is a view in top plan of the opener of Figure 12;

Figure 15 is a vertical section on an enlarged scale on the line 15—15 of Figure 12;

Figure 16 is a vertical section through the upper part of the opener of Figure 12 corresponding with the section of Figure 15, but showing the drive roller and associate parts in lowered in-operative position;

Figure 17 is a view in side elevation of a fourth embodiment of the present invention, showing 30 the driving roller and associate parts in raised or operative position;

Figure 18 is a sectional view on the line 18—18 of Figure 17;

Figure 19 is a view in elevation of the can side 35 or face of the opener shown in Figure 17;

Figure 20 is a vertical section on an enlarged scale on the line 20—20 of Figure 17;

Figure 21 is a vertical section corresponding to Figure 20 but showing the drive roller and associate parts in lowered position;

Figure 22 is a detailed view showing a modified form or alternate type of cam pawl.

Referring now more particularly to the drawings, wherein like numerals of reference indicate corresponding parts throughout the several views, the description will first be directed to the construction and operation of that embodiment of the invention which is particularly illustrated in Figures 1 to 5 inclusive.

The device as illustrated in these figures comprises the flat relatively long body plate 1 which, as illustrated, is designed to assume a vertical position for use, being secured to a supporting bracket, as hereinafter described. This body plate 1 at its upper end is provided with the offset longitudinal extensions 2 whereby there is formed a downwardly facing shoulder 2^a, Figure 3, for the purpose hereinafter stated. At its upper end the reduced portion 2 merges into the horizontal lateral extension 3 which in turn merges into or connects with the reverted downturned portion 4 which constitutes the cutting blade and which at its lower edge is obliquely cut and sharpened to provide the oblique cutting edge 5. With this oblique formation of the cutting edge it will be seen that when the point of the edge is thrust through the top of a can, as illustrated in Figure 3, it will extend through the can top at an angle and as the can is rotated the metal of the top will advance toward and against the inclined or angled cutting edge so that the penetration of the blade through the can top while the can is being rotated, will be made easily.

The blade 4 and the portion 2 of the plate body

are in spaced parallel relation as shown and there extends between these two portions a pivot stud 6 which, as shown in Figure 3, is secured to the portion 2 while its opposite end extends into an opening in the blade portion but is not secured to this portion and consequently there is permitted a slight movement of the blade portion relatively to the portion 2. Such movement may occur where an outward thrust occurs against the sharpened edge of the blade when the blade is being forced through the top of a can and the movement is permitted by the resiliency of the metal.

The pivot stud 6 has supported thereon an idler roller 7. The periphery of the idler roller 7 is knurled and this knurled edge bears against the rim of the can while the head of the same is being cut. At one side of the knurled roller 7 is a flange 7^a which extends across the bead at the edge of the can when the bead is in engagement with the edge of the roller.

The body 1 has formed therethrough, just beneath the offset shoulder 2^a, the longitudinally extending elongated opening 8. Extending through this opening 8 is a sleeve 9 which has formed integral therewith and substantially midway of its ends, the circular collar 10, the diameter of which is only slightly less than the width of the opening 8 in which this collar is positioned. The sleeve 9 at each side of the collar is flattened, as indicated at 11, in Figures 10 and 11, for the purpose hereinafter stated.

Extending through the sleeve 9 is a relatively long bearing sleeve 12 and passing through this bearing sleeve is a shaft 13 which, at the end remote from the cutting blade, is reduced and squared, or given any desired polygonal cross-section, to receive a similarly formed opening in the end of an operating handle or crank arm 14. The reduced end of this shaft is indicated by the numeral 15 and, as shown in Figure 3, it is provided with a suitable head 16 which secures the handle to the shaft.

Secured in a suitable manner to the opposite end of the shaft 13 is a driving wheel 17, the periphery of which is toothed, as shown in Figure 5^a. As is shown in Figure 3, the face of this toothed driving wheel 17 lies in a plane just inside of the inner face of the cutting blade 4. In other words, there is just sufficient space between the plane of the face of the wheel 17 and the inner face of the cutting blade 4 to receive the double thickness of metal made up of the side wall and the inturned portion of the can head which is formed when the cutting blade is thrust therethrough. If the thickness of such metal varies, then the resiliency of the metal from which the cutting blade is formed will permit the blade to spring slightly away from the portion 2 so that the wheel 17 will not be bound so as to make its turning difficult. As previously stated, the sliding connection between the blade 4 and the adjacent end of the pivot stud 6 permit this slight springing movement of the blade with respect to the part 2.

In Figure 3 a portion of a can is outlined and is indicated by the reference character 18. As shown, the driving roller 17 is in raised position so that the cutting edge 5 of the blade 4 has been forced through the top of the can and the bead of the can is shown engaged between the driving roller 17 and the idling roller 7.

Interposed between the plate body 1 and the driving wheel 17 is an eccentric wheel 19 which has an eccentrically positioned opening for the

reception of the adjacent end of the sleeve 9, as shown in Figure 3. This eccentrically located opening in the eccentric wheel 19 has a portion of its edge flattened to correspond with the flattened portion 11 of the adjacent end of the sleeve 9 and the edge of the sleeve is flared, as shown in Figure 3, to prevent axial movement of the eccentric wheel on the sleeve. The eccentric wheel is tightly bound or secured between the end of the sleeve 9 and the collar 10 and consequently it cannot have movement around or axially of the sleeve 9 independently of the sleeve.

As is shown in dotted outline in Figure 1, the eccentric wheel has a portion of its periphery extended to form a ninety degree angle, thus providing two stop faces 20 and 21. The action of these stop faces will be hereinafter more specifically described.

Upon the opposite side of the collar 10 from the eccentric wheel 19 there is mounted upon the sleeve 9 an end of a lever arm 22. This lever arm 22, like the eccentric wheel 19, has the opening in which the end of the sleeve 9 engages, flattened, as shown in Figure 10, to engage the flattened portion of the sleeve so that the arm 22 will be held on the sleeve against turning. Also the end of the sleeve is flared, as shown, to hold the arm against axial movement thereon. This flared end of the sleeve 9 secures the upper end of the lever arm 22 against the outer side or adjacent side of the collar 10.

Substantially midway of its ends the lever arm 22 is right angularly offset, as indicated at 23, so that the lower end of this arm will clear the cam pawl 24 which is pivotally attached to the body plate 1 by the rivet 25. This pawl 24 has its lower edge arcuately formed, as indicated at 26, which arc is eccentric to the pivotal center for the pawl, as shown in Figure 1, and as herein-after more particularly described.

At its free end the lever arm 22 has each edge cut in to form a long notch 27, the longitudinally extending face of which is at an oblique angle with respect to the adjacent longitudinal edge of the arm, to be engaged by the hereinafter described crank arm carried slide.

The plate body 1 carries the stop pin 28 which is engaged by the pawl 24 so that the forward swinging movement of the pawl is limited to the position in which it is shown in Figure 1. It will also be noted that when the eccentric wheel has been turned to the position shown in Figure 1 where the driving wheel 17 has been raised to the limit of its movement, as in the operation of forcing the point of the knife blade through the top of the can, the trailing edge of the lever arm 22 will be in a horizontal plane which is slightly above the lowermost point or end of the camming edge 26.

The crank arm or handle 14 carries a knob or hand grip 29 upon its free end and upon the side nearest the lever arm 22 is a sliding latch unit 30. This unit comprises two spaced strips of material which are indicated by the numeral 31 and which together form a guideway 32 in which is slidably disposed a slide or trip 33. This slide carries the two transversely extending movement limiting pins 34 which engage in slots 35 formed in the opposite ends of the strips 31. Upon the outer end of the slide 33, that is, the end nearest the knob 29 of the handle, there is a longitudinally extending stud 36 which engages in one end of an expansion spring 37, the other end of this spring having engaged therein the finger 38 which is secured to the handle, as 75

shown in Figure 2. Thus the slide 33 is constantly urged toward the inner or pivoted end of the handle, and it is so positioned that when the handle is turned in a clockwise direction the slide will overlap the notched end of the lever arm 22, to a substantial extent, preferably about one-eighth of an inch.

Upon the side of the plate body 1 adjacent which the eccentric wheel is located there is secured at the lower end of the plate body a plate 39 which is formed integrally with an end of a spring arm 40 which curves upwardly and extends over the top edge of and in relatively closely spaced relation to the plate 39, as is shown in Figures 1 and 2. The top edge of this spring arm 40 is contacted by the peripheral edge of the eccentric wheel and forms a bearing or thrust surface for the eccentric wheel, as will be readily understood. Only a slight clearance is allowed between the spring arm 40 and the top edge of the plate body 39, with which it is integrally connected, so that if an unusual amount of pressure or force must be applied to the handle 14 in causing the knife blade to penetrate the top of the can the spring arm cannot yield to such a great extent as to defeat the operation of the device.

There is also secured, as shown in Figure 3, to the lower end of the body plate and across the spring plate 39, an end of a supporting or bracket arm 41, these parts being preferably secured together by rivets 42, although any other suitable means of coupling these parts together may be employed if desired. The opposite end of the bracket arm 41 is formed to provide a T or cross head 41' which is designed to be slidably engaged in a wall attached holder a between the back of the latter and the inturned flanges b which are disposed along opposite edges of the holder back. One of the flanges b has formed in its longitudinal free edge a notch c. Secured to the side of the bracket 41 adjacent the notched edge of the flange b of the carrier or holder, is one leg of a substantially U-shaped spring d. The secured leg of this spring is indicated by the letter e and the other leg, which is indicated by the letter f, slides at its free end along the edge of the notched flange b and engages in the notch c, as shown in Figure 2, to hold the bracket against disengagement from the holder a. While the spring has been shown upon the side of the bracket arm 41, on which the crank is located, it will be obvious that it may be placed upon the opposite side of the bracket arm if desired, particularly where a short arm may be employed, so that the spring will not interfere with the operation of the crank. With this locking means for the spring the bracket arm is prevented from jumping upward when an upward pull is applied to the handle 29.

In the operation of the device, the driving wheel together with the sleeve 9 and the collar 10 will be in lowered position at the beginning of the procedure for applying and cutting the top from a can. The eccentric wheel will be turned to the position where the stop face 21 thereof will be in contact with the top of the spring arm 40 and the lever arm 22 will be extended rearwardly and downwardly, as shown in dotted outline in Figure 1. After the rim or bead at the edge of the can top has been inserted in the customary manner with rotary cutters of this character so that it is above the driving wheel and the end of the can is above the cutting blade, the handle or crank arm 14 will be turned

from its downwardly extending or hanging position in a clockwise direction until the end of the slide 33 comes to rest upon the upwardly facing notch 27 of the lever arm 22. The lever arm will then be forced down by continued rotation of the handle, causing rotation of the eccentric wheel and consequently the raising of the driving wheel toward the overlying idler wheel 17. During this operation the driving wheel 17 will be turning and consequently as the point of the knife blade is forced into the top of the can the can will also be rotated and the penetration of the blade will be made relatively easy.

As the slide 33 moves around against and with the lever arm 22 its free end will ride under the cam pawl, engaging the edge 26 thereof and the slide will be gradually forced back against the tension of the spring 31 until the slide is in a direct vertical line with the pivotal center of the shaft 13, where it will be forced beyond the end of the lever arm 22 so as to release the latter, and it will then slide off of the lowest point of the cam pawl. The eccentric wheel will then be turned to a position where the stop face 20 is slightly spaced from the shoulder 2^a, as shown in Figure 1. A slight clearance is provided here between the stop face 20 and the shoulder 2^a to allow for some slight further turning of the eccentric wheel if this should be necessary.

After the can head or top has been cut completely around, the parts of the device may be restored to inoperative position ready to receive another can by giving a counterclockwise rotation to the handle 14 through about one-quarter turn from the lowermost or hanging position of the handle which will cause the slide 33 to engage in the opposite notch 27 of the lever arm from the one previously engaged, until the lever arm has been swung back to the dotted line position shown in Figure 1, whereupon the cam wheel 10 will be in the lower end of the slot 8 and the driving wheel 17 turned to its lowest position. The handle when released will gravitate back to hanging position and also the cam pawl will normally remain suspended from its pivot in the manner shown, and it is merely turned counterclockwise on this pivot when engaged by the slide until rotated to the point where it escapes the slide, at which time the action of gravity will cause it to return to its normally depending position against the rivet stop.

Figures 6 to 9 inclusive illustrate another embodiment of the invention wherein the vertical plate body is indicated by the numeral 1^a. This is secured at its lower end to the supporting bracket 41^a while at its upper end it is shaped to provide the offset parallel and longitudinally extending portion 43, which is reversely right angularly bent at its upper end, as indicated at 44, and terminates in the downwardly directed blade 45, which has the cutting edge 5^a, which is downwardly directed in a plane paralleling the offset portion 43. By the provision of the offset portion 43, there is provided the eccentric wheel bearing shoulder 45.

In the offset portion 43 of the plate body there is provided the longitudinally extending guide slot 8^a. Disposed within and extending through this guide slot 8^a is the sleeve 9^a, which intermediate its ends has the encircling collar 10^a which turns and moves lengthwise in the guide slot in the operation of the instrument.

Upon the can side of the plate, the sleeve 9^a supports an eccentric wheel 19^a, which bears

against the shoulder 45 and against the under side of the angled top portion 44 of the plate, as shown in Figures 6 and 8. A portion of the periphery of this wheel is angled to provide the stop faces 20^a and 21^a which engage, respectively, with the part 44 and the shoulder 45 to limit the rotation of the wheel.

The end of the bearing sleeve 9^a is swaged over or flanged, as shown in Figure 9, like the sleeve 9, to secure the eccentric wheel 19^a against axial movement and a portion of this sleeve where it passes through the eccentric wheel, is flattened like the portion 11 of the sleeve 9, to engage a correspondingly flattened portion of the edge of the opening in the eccentric wheel through which the sleeve end extends.

Upon the opposite side of the plate portion 43, from the eccentric wheel 19^a, the sleeve 9^a passes through an opening in an end of the lever 22^a and this end of the sleeve is secured to the lever to hold the latter against axial movement and also to hold it against turning independently of the sleeve, in the same manner as the lever 22 is secured to the sleeve 9.

Extending through the sleeve 9^a is a bearing sleeve 12^a corresponding to the sleeve 12, shown in Figure 3.

Extending through the bearing sleeve 12^a is a drive wheel supporting shaft 13^a, which has upon the end thereof nearest the cutting blade 45, the peripherally knurled or toothed driving wheel 17^a, which lies in a plane inside of the plane of the blade 45, as shown in Figures 8 and 9. The opposite end of this shaft extends beyond the bearing sleeve and is squared or otherwise suitably shaped to engage in a correspondingly formed opening in an end of a crank arm 14^a, which upon its opposite end carries the handle 29^a. A head 16^a formed upon the end of the shaft 13^a maintains the crank 14^a in position thereon. This head may be in the form of a threaded on nut or it may form a swaged over portion of the end of the shaft.

As shown most clearly in Figure 9, the plate 1^a is secured to the supporting bracket 41^a by the two rivets 54 and 55. The rivet 54 pivotally supports beneath the shoulder 45, a cam pawl 24^a, the forward swinging movement of which is limited by the stop pin or stud 28^a. This cam pawl is formed like the pawl 24 with an eccentric lower camming edge 26^a.

The crank 14^a supports a slide unit, indicated as a whole by the numeral 30^a, which comprises a pair of guides, one only of which is shown and indicated by the numeral 31^a, between which is slidably mounted the slide plate 33^a. This plate is normally urged toward the pivoted end of the handle 14^a by the spring 31^a so that the slide plate 33^a coacts with the notched end of the lever arm 22^a, the notches of which arm are indicated by the numerals 27^a, to turn the eccentric wheel 19^a for the operation of the parts in the same manner as described in connection with the structure shown in Figure 1.

The operation of the second embodiment of the invention will be seen to be substantially the same as that of the embodiment shown in Figure 1, in that when the eccentric wheel 19^a is rotated counterclockwise, the flattened edge portion 21^a will come into contact with the shoulder 45 and stop the movement of the wheel in this direction and the shaft with the parts carried thereby will be moved to the lower end of the slot 8^a and the lever 14^a will be swung rearwardly from the operative position in which it is

shown in Figure 7. Clockwise rotation of the crank 14^a after the can 18^a, Figure 9, has been placed in position, will effect the contact of the slide 33^a with the lever 22^a and movement of the lever so as to turn the cam wheel until the top edge 20^a contacts the top part 44 of the body of the instrument, whereupon the driving roller and other parts will be moved upwardly to lift the can, forcing the cutting edge of the knife through the top thereof while it is being rotated. The cam pawl 24^a and the slide 33^a coact as in the structure shown in Figure 1, to disengage the slide from the lever so that continued clockwise rotation of the handle may take place.

Figures 12 to 16 inclusive, show the third embodiment of the invention. In this embodiment the body plate 1^b is straight throughout its length and at its upper end has the laterally extending or angled head plate 57 which terminates in the downwardly extending knife 4^b, the lower edge of which is beveled or sharpened to form the cutting edge 5^b. The upper part of the plate body 1^b has formed therein the longitudinally extending guide slot 8^b. Disposed in and extending transversely through this guide slot is a bearing sleeve 12^b and extending through the bearing sleeve is a shaft 13^b upon one end of which is carried the driving wheel or roller 17^b. This roller is, of course, like the rollers of the other embodiments of the invention, disposed in a plane just inwardly of the cutting blade 4^b, so that it may engage the rim of a can 18^b, as shown in Figure 16, to shift the same upwardly to the position shown in Figure 15, so as to force the knife through the top or head of the can.

Extending across the rear edge of the body plate 1^b and partly enclosing the body plate, is a substantially U-shaped yoke 58 which has the two spaced parallel side portions 59 and 60 joined by the short intermediate portion 61 which, as shown in Figure 14, is spaced a substantial distance rearwardly from the edge of the plate body. The two sides 59 and 60 of the yoke are suitably apertured to receive the ends of the bearing sleeve 12^b with which they are keyed, as is clearly shown in Figures 15 and 16, the keys being indicated by the numeral 62. The side 60 of the yoke is interposed, as shown in Figures 15 and 16, between the toothed or knurled driving wheel 17^b and the adjacent plate body 1^b, and this portion of the yoke has the offset depending tongue 63 which is pivotally coupled by means of a pivot pin or rivet 64 with an end of a link 65, the other end of which link is pivotally secured by the rivet or pivot pin 66 to the body plate 1^b in longitudinal alignment with the center of the guide slot 8^b and the driving wheel shaft extending therethrough. The pivot 64 thus forms a joint or elbow between the depending tongue 63 which forms an integral part of the yoke and the link 65 which is permitted pivotal movement only through its connection with the body by the pivot 66. This joint or elbow is adapted to swing or bend forwardly slightly beyond longitudinal center on which the pivot 66 and the shaft 13^b lie in its movement past the center line 65 is limited by the stop pin 67, as is clearly shown in Figure 13.

Upon the opposite side of the plate 1^b from the joint or elbow 64, the side 59 of the yoke carries the depending and laterally offset lever 22^b.

Between the lever 22^b and the body 1^b, there is pivotally supported on the body by the pivot pin 68, the cam pawl 24^b, which like the cam 75

pawls of the other embodiments, has a lower eccentric camming edge 26^b.

The end of the shaft 13^b remote from the driving wheel is suitably formed for the attachment thereto of an end of the crank 14^b at the outer end of which is a handle 29^b. Like the cranks of the other embodiments, this crank handle 14^b carries a slide unit which is generally indicated by the reference character 30^b, and which is shown only in dotted outline in Figure 12. The construction and operation of this slide unit is exactly the same as that shown in Figures 1 and 2 and, therefore, a detailed illustration and description of the same in connection with this modification is not considered necessary.

The lower end of the plate body 1^b is fixed by the rivets 69 to the supporting arm 41^b, which is constructed and attached to a suitable supporting body in the same manner as the previously described arm 41. In this embodiment also the forward swinging movement of the cam pawl 24^b is limited by a stop pin which is secured to the body 1^b, and is indicated by the numeral 70.

The operation of this embodiment is substantially the same as the previously described ones in that when the crank handle is turned clockwise, the slide 33^b strikes the lever 22^b to oscillate it a predetermined distance to the position in which it is shown in Figure 12. In so oscillating this lever, the joint or pivot 64 is bent from a forwardly broken position where it is moved beyond the longitudinal center of the plate body from the stop 67 rearwardly into near engagement with the stop, as shown in Figure 13, and in being so moved, it raises the shaft 13^b from the lower end of the slot 8^b to the upper end thereof, thus forcing the driving wheel upwardly and lifting the can so that the cutting knife edge will be forced through the top of the can, as shown in Figure 15. The cam pawl functions as in the other embodiments, to shift the slide out of engagement with the lever 22^b when the driving wheel has been raised and the knife edge forced through the can top.

Figures 17 to 21 illustrate the fourth embodiment of the invention. In this form there are employed two elongated parallel body plates which are designated 71 and 72. The upper ends of these plates are obliquely angled, as shown in Figure 18, and indicated by the reference characters 71' and 72', and have interposed therebetween a spacer annulus 73. At their lower ends there is interposed between the body plates to maintain them in spaced relation, the spring plate 39^a, with which is integrally formed a rearwardly, upwardly and forwardly curving spring arm 40^a. The terminal portion of this spring arm which extends forwardly with respect to the instrument, is disposed between the body plates 71 and 72. The obliquely angled portions 71' and 72' are provided with suitable aligned openings 74, which are coaxial with the annular spacer 73 and extending through these openings is a sleeve 75 having the encircling collar 76 which is fitted in the annular spacer 73 and secured between the adjacent portions of the body plates. This sleeve has extended therethrough a cutter wheel shaft 77, and the end of this shaft, which is upon the same side of the implement as the head 12^d, is reduced and screw-threaded, as indicated at 77', to receive a cutter wheel 78. Upon the inner side of the cutter wheel there is mounted on the shaft carrying the cutter a roller

collar 79, the periphery of which is knurled, as shown in Figure 18, and integrally formed with this collar is a flange 80 which is of a diameter greater than the collar and which is provided to engage against the outer side of the can rim, as shown in Figure 18, when the can has had its top punctured by the edge of the wheel. A portion of a can is shown in dotted outline in Figure 18 and is indicated by the numeral 18^c and, as is shown, when the can is being cut by the wheel 78 the flange engages the knurled collar 79 and is securely held between the same and the underlying driving wheel, as hereinafter described.

The opposite end of the cutter wheel shaft 11 carries a head 81, the overall diameter of which is substantially the same as that of the sleeve 75. Interposed between this head and the adjacent end of the sleeve 75, and encircling the shaft 11, is a yieldable spring washer 82 which functions to draw the flange portion 80 of the roller cutter against the opposite end of the sleeve 75, but permits the cutter wheel to have some movement axially with respect to the sleeve so that the cutter wheel and the hereinafter described driving wheel may separate slightly where a can seam is encountered, or in the event that a can having metal of unusual thickness is encountered.

Below the angled portions 11' and 12' of the body plates, the two plates are provided with the longitudinally extending aligned guide slots 8^c. Extending transversely of the body plates through the slots 8^c is a bearing sleeve 12^c, which upon the end nearest the side of the instrument upon which the cutter wheel is located, has the enlarged head 12^a, which fits in the adjacent slot 8^c. Interposed between the plates 11 and 12 and located between and in contact at its periphery with the spacer 73 and the spring arm 40^a, is an eccentric wheel 19^b, through which is eccentrically extended the bearing sleeve 12^c. This bearing sleeve is locked or keyed to the eccentric wheel by the key 62^a. Integral with and extending radially from the periphery of the eccentric wheel 19^b is a stop finger 18^c which functions in the same manner as the stop shoulders 20 and 21 of the eccentric wheel shown in Figure 1. In other words, this stop finger will stop just below or in spaced relation to the annular spacer 73, but due to manufacturing tolerances or any wear as a result of usage over a long period of time, this spacing or tolerance permits of any further rotation required to effect escapement of the arm 22^c from the slide unit 30^c. This tolerance is not sufficient to affect the height of the driving wheel 11^c, nor to interfere with the efficient operation of the device. Also, upon counter-clockwise rotation of the eccentric wheel the finger 18^c will come down into contact with the end of the spring arm 40^a and likewise limit the return turning movement of this element.

Upon the side of the device opposite from the bearing sleeve head 12^a, the bearing sleeve 12^c is encircled by a collar 83 which extends at one end into the adjacent guide slot 8^c and engages against the adjacent side of the eccentric wheel. At the outer end of this collar 83 the lever 22^c bears and is keyed to the bearing sleeve 12^c by a key similar to the key 62^a which couples the eccentric wheel with this bearing sleeve. Thus, the lever 22^c and the eccentric wheel 19^b are locked together to turn as a unit with the bearing sleeve 12^c.

Extending through the bearing sleeve is a driving wheel shaft 13^c which carries upon the end

adjacent the rotary cutting knife 78, the periphery knurled or toothed driving wheel 11^c. By reason of the angular disposition of the axis of the rotary knife 78, it will be seen upon reference to Figures 18, 20 and 21, that the outer face of the driving wheel is in a plane parallel with the rotary knife upon the inner side of the cutting edge thereof and, consequently, when the driving wheel is shifted upwardly by the movement of the bearing sleeve in the guide slots 8^c, the top flange or bead of the can 18^c will be moved along the inner face of the knife into engagement with the cooperating roller 78 between which and the driving wheel it will be gripped, so that the necessary rotary movement may be imparted to the can by the driving wheel. At the same time the cutting edge of the rotary knife will penetrate the head of the can and the flat inner face of the knife will smooth down the metal at the wall of the can so as to cut out the can top smoothly and without leaving a rough or jagged edge of metal. In all of the other embodiments of the invention also, it will be observed that the knives bear against the inner face of the can wall after penetrating the head of the can, to smooth down the metal and prevent leaving a rough or jagged edge.

Secured to the side of the instrument opposite from the driving wheel and cutting knife and below the guide slots 8^c is a bracket 85 which carries a spaced parallel portion 86 which is in spaced parallel relation with the lever 22^c. The part 86 of the bracket 85 carries a pivot pin 87 on which is pivotally suspended a cam pawl 24^c having, like the cam pawl 24, the eccentric lower camming edge 26^c. The lower end of the lever 22^c swings across this cam pawl as in the other embodiments of the invention.

The outer end of the shaft 13^c has fixed there-to an end of the crank 14^c which carries at its free end the handle 28^c and upon this crank is a slide unit 30^c which is shown in Figure 17 in dotted outline and which, like the unit 30^b shown in Figure 12, is of exactly the same construction as the unit which is shown in detail in connection with Figures 1 and 2. The slide of this unit coacts with the lever 22^c as in the other embodiments of the invention to turn the eccentric wheel and move the can into and out of engagement with the cutter wheel 78.

It will be readily recognized that in this fourth embodiment of the invention, the general principle of operation is the same as in the other embodiments described in that upon clockwise rotation of the handle, the slide which is carried upon the crank arm will engage the depending lever and force it down to the position in which it is shown in Figure 17, thus turning the eccentric wheel which bears upon the spring arm 40^a and which, when so turned raises the driving wheel shaft and the bearing sleeve encircling it to the upper end of the guide slots 8^c. This forces the top flange of the can past the cutting knife and forces the knife through the head of the can. The cam pawl then functions to shift the slide from engagement with the lever so that continued clockwise rotation of the crank may be had.

As in the other embodiments of the invention, the device shown in Figure 17 is designed to be supported upon a horizontal supporting arm, such arm being here indicated by the numeral 41^c and being secured to the lower ends of the plates 11 and 12 against the side of the plate

72 by the rivets or holding devices which secure the spring plate 39^a in position.

In Figure 22 there is illustrated a modified form of cam pawl which might be substituted for the cam pawls shown in the several embodiments of the invention. This modified form of cam pawl is indicated by the numeral 88 and is oscillatably supported upon a pivot pin 89 carried by a supporting body 90. The free or outer end of the modified cam pawl is provided with a notch 91 in which the slide of the crank engages. This cam pawl is normally maintained in a rearwardly and downwardly extending position with respect to the supporting body plate by the spring 92, one end of which is secured to the pivot pin 89 on which the pawl is rockably supported while the other end is connected with the pawl, as indicated at 93. The bias of the spring is such as to cause it to swing the pawl to the angled position in which it is shown where the spring is no longer under tension. When the crank is turned and the slide carried thereby engages in the notch 91, the pawl will be forced to turn on its pivotal support in a clockwise direction and it will place the spring under tension. At the same time, due to the different centers of rotation for the handle and the pawl, the pawl will urge the slide to move outwardly so that it will be disengaged from or shifted beyond the end of the adjacent lever and thereby freed from the lever. When the pawl has swung around below vertical center, the slide will then slip out of the notch 91, so as to permit the spring 92 to swing the pawl back to inoperative position and free the crank for continued clockwise turning.

From the foregoing, it will be readily apparent that a novel feature which is common to the several forms or embodiments of the invention resides in the means by which the penetration of the can head or top by the cutting knife is accomplished simultaneously with the rotation of the crank handle so that it is not necessary to manipulate a separate element for forcing the knife through the can head, as is the case with other rotary cutters. It will also be seen that due to the fact that the driving wheel which is in engagement with the top flange of the can, is being rotated while the can is being forced up into engagement with the top penetrating 50 knife, the knife cuts through the top of the can with a shearing motion rather than being forced directly through as in the case of other types of cutters and consequently, this action of forcing the knife through the top of the can is accomplished with much less effort than in other types of cutters.

It will also be observed that in the different embodiments of the present invention, a single rotation of the crank counter-clockwise after the can head has been cut out, effects the lowering of the driving wheel from the knife so that the can can be readily removed by the engagement of the slide carried by the crank with the oscillating lever which is operatively coupled with the eccentric wheel or with the mechanism by which the driving wheel is raised and the instrument is left with the parts thereof set ready for the reception of another can.

As previously stated, in the operation of all of the embodiments of the invention a single series of clockwise rotations of the operating handle or crank forces the cutter through the end of the can, effects the firm engagement or attachment of the can in the device, and also cuts 75

the end from the can, and subsequent clockwise turning of the handle, which does not have to exceed one and one-quarter turns, releases the can from the device. If preferred, after the can end has been completely cut out the operating handle may be further rotated clockwise until the slide on the operating handle has passed over the lever arm which it operates, before beginning counter-clockwise rotation of the handle to release the can from the device. In such case, counter-clockwise rotation of the operating handle does not exceed a quarter turn.

It will also be apparent that in all of the embodiments, when the cutter is being forced 15 through the top of the can and the can is being firmly engaged or secured, the operating handle is being pulled toward the operator so that maximum leverage is obtained and the operation of the device is effected by the operator with a 20 minimum of effort. Also, when operating the handle counter-clockwise a minimum of effort is required for releasing the can, due to the fact that during this portion of movement the handle is being pushed away from the operator.

25 In all forms it will be noted that the driving wheel moves only vertically in relation to the cutter or the cooperating roller. This provides for better alignment of the can while being engaged in the device, and while engaged, and also 30 while being disengaged or released. The design in each form is also such as to provide for a good substantial construction and plenty of operating tolerances so that the devices will continue to operate efficiently even after having been used 35 for a considerable length of time.

The alternate type of cam pawl shown in Figure 22 provides for greater ease of operation and eliminates the clicking of the slide during operation of the handle, as the slide passes over the 40 other type cam pawl.

In the forms of the invention shown in Figures 1 and 17 the spring arm below the eccentric wheel provides for uniform pressure of the driving wheel against the can rim, insuring greater 45 ease of operation, positive traction of driving wheel with the rim of the can, but with a minimum of pressure thereagainst. The spring also provides for positive traction of the driving wheel with rims of varying height without perceptible variation in the amount of effort required to operate.

Also, it will be observed that in the forms of the invention shown in Figures 1, 6 and 12 the cutter is forced through the can diagonally since 55 the can is being rotated by the driving wheel, while it is also being forced upward by the driving wheel. This provides for piercing the can top with less effort than is required where a vertical or longitudinal movement only is employed. In the form shown in Figure 1 the cooperating roller above the driving wheel provides for still greater ease of operation.

The form of the invention shown in Figures 6 to 9 is such that it may be produced at a most economical production cost due to the condensed character of the same.

In the structure shown in Figures 12 to 15 the toggle action illustrated and described provides for still greater ease of the operation of forcing the cutter through the can. It will also be apparent that the cooperating roller which is employed in the structure of Figure 1 may also be employed in this embodiment of the invention.

What is claimed is:

1. A can opener of the character stated, com-

prising a body member, a knife carried thereby, a can flange engaging driving wheel rotatably supported on the body member for movement relative to the knife, a thrust element having operative connection with said wheel for imparting movement thereto relative to the knife, the thrust element having operative connection with the body member, a lever means operatively connected with the thrust element for effecting movement of the latter, a crank connected with said wheel for imparting rotary motion thereto, and means carried by the crank for intermittent connection with the lever upon turning of the crank and wheel to effect oscillation of the lever and actuation of the thrust means for moving the wheel relative to the knife.

2. A can opener of the character stated, comprising a body member, a knife carried thereby, a can flange engaging driving wheel rotatably supported on the body member for movement relative to the knife, a thrust element having operative connection with said wheel for imparting movement thereto relative to the knife, the thrust element having operative connection with the body member, a lever means operatively connected with the thrust element for effecting movement of the latter, a crank connected with said wheel for imparting rotary motion thereto, means carried by the crank for intermittent connection with the lever upon turning of the crank and wheel to effect oscillation of the lever and actuation of the thrust means for moving the wheel relative to the knife, said last means comprising a movable contact member on the crank engaging with a side of the lever upon turning of the crank, and a camming means carried by the body member and engaged by the contact member and functioning to shift the latter out of engagement with the crank after a predetermined period of movement of the crank.

3. A can opener of the character stated, comprising a body member, a knife carried thereby, a can flange engaging driving wheel rotatably supported on the body member for movement relative to the knife, a thrust element having operative connection with said wheel for imparting movement thereto relative to the knife, the thrust element having operative connection with the body member, a lever means operatively connected with the thrust element for effecting movement of the latter, a crank connected with said wheel for imparting rotary motion thereto, and means carried by the crank for intermittent connection with the lever upon turning of the crank and wheel to effect oscillation of the lever and actuation of the thrust means for moving the wheel relative to the knife, said thrust means comprising an eccentric wheel having bearing on a fixed fulcrum surface carried by the body member.

4. A can opener of the character stated, comprising a body member, a knife carried thereby, a can flange engaging driving wheel rotatably supported on the body member for movement relative to the knife, a thrust element having operative connection with said wheel for imparting movement thereto relative to the knife, the thrust element having operative connection with the body member, a lever means operatively connected with the thrust element for effecting movement of the latter, a crank connected with said wheel for imparting rotary motion thereto, means carried by the crank for intermittent connection with the lever upon turning of the crank

15 and wheel to effect oscillation of the lever and actuation of the thrust means for moving the wheel relative to the knife, a yieldable body carried by the body member, and said thrust means comprising an eccentric wheel having peripheral bearing upon said yieldable body.

5. A can opener of the character stated, comprising a body member, a cutter carried by the body member, a bearing sleeve supported transversely of the body member for movement relative to the cutter, a shaft extending through and rotatable in the bearing sleeve, a driving wheel at one end of the shaft disposed in a plane closely paralleling the cutter for movement with the sleeve relative to the cutter, means for imparting rotary motion to the shaft and driving wheel, a thrust element operatively coupled with the bearing sleeve, means providing a fulcrum for the thrust element, said thrust element being movable in either of two directions for selectively shifting the driving wheel toward or away from the cutter, a movable means connected with said sleeve for imparting movement to the thrust element, and means carried by the shaft rotating means for engaging the said means connected with the thrust element during a part of the rotary movement of the shaft whereby the thrust element will be actuated to effect relative movement between the cutter and said wheel.

20 6. A can opener, comprising a body member, a knife connected with the body member, a bearing sleeve supported by the body member for movement toward and away from the knife, the sleeve being rotatable, a shaft extending through said sleeve for rotation therein and for movement therewith relative to the knife, a can rim 25 engaging driving wheel connected with the shaft for movement relative to the knife, a thrust element coupled with the sleeve, means forming a fulcrum for the thrust element, the thrust element having two directions of movement for selectively moving the driving wheel toward and away from the knife, a lever operatively coupled with the sleeve for imparting rotary motion 30 thereto, a crank coupled with the shaft for turning the same, a movable element supported on the crank for engagement with a side of the lever upon rotation of the crank, and means for shifting the movable element after a predetermined extent of movement of the lever thereby 35 to effect disengagement of the movable element from the crank.

40 7. A can opener, comprising a body member, a knife connected with the body member, a bearing sleeve supported by the body member for movement toward and away from the knife, the sleeve being rotatable, a shaft extending through said sleeve for rotation therein and for movement therewith relative to the knife, a can rim 45 engaging driving wheel connected with the shaft for movement relative to the knife, a thrust element coupled with the sleeve, means forming a fulcrum for the thrust element, the thrust element having two directions of movement for selectively moving the driving wheel toward and away from the knife, a lever operatively coupled with the sleeve for imparting rotary motion 50 thereto, a crank coupled with the shaft for turning the same, an element supported on the crank for movement toward and away from the shaft, resilient means normally urging movement of the element toward the shaft, said element being engageable with a side of the lever upon rotation of the crank and shaft to impart movement to 55 the lever and rotary motion to said sleeve to

effect movement of the thrust element, and cam means carried by the body in position for engagement by the movable element and constructed and arranged to shift the movable element away from the shaft to effect its disengagement from the lever after the latter has been moved a predetermined distance.

8. A can opener, comprising a body, a cutter carried thereby, a bearing sleeve rotatably supported on the body for movement relative to the cutter, a shaft rotatably supported in the sleeve to be carried thereby, a can flange engaging driving wheel carried by the shaft for movement therewith relative to the cutter, an eccentric wheel secured eccentrically to the sleeve between the same and a portion of the body member, means providing a fulcrum against which the periphery of the eccentric wheel bears, the eccentric wheel upon rotation effecting the shifting of the sleeve with the driving wheel toward and away from the cutter, a lever secured to the sleeve upon the opposite side of said body member from the eccentric wheel, a crank connected to the shaft for imparting rotary motion thereto, and a shiftable element carried by the crank for engagement with the lever upon rotation of the crank, the shiftable element when shifted in one direction on the crank being removable from its connection with the lever.

9. A can opener, comprising a body, a cutter carried thereby, a bearing sleeve rotatably supported on the body for movement relative to the cutter, a shaft rotatably supported in the sleeve to be carried thereby, a can flange engaging driving wheel carried by the shaft for movement therewith relative to the cutter, an eccentric wheel secured eccentrically to the sleeve between the same and a portion of the body member, means providing a fulcrum against which the periphery of the eccentric wheel bears, the eccentric wheel upon rotation effecting the shifting of the sleeve with the driving wheel toward and away from the cutter, a lever secured to the sleeve upon the opposite side of said body member from the eccentric wheel, a crank connected to the shaft for imparting rotary motion thereto, an element carried by the crank for limited movement lengthwise thereof, resilient means normally urging movement of the element toward the pivoted end of the crank, the element being arranged for engagement with a side of the lever during rotation of the crank to impart turning movement to the lever, and a camming element supported adjacent the end of the lever for engagement by the crank carried element to effect the movement of the latter outwardly against the tension of the resilient means and disconnection of the crank carried element from the lever.

10. A can opener, comprising an elongated plate having a laterally offset parallel end portion providing a shoulder, a knife connected at the terminus of the offset portion, said offset portion having a longitudinally extending guide slot bearing, a bearing sleeve extending through the guide slot for rotation therein and movement longitudinally thereof, an eccentric wheel eccentrically secured to the bearing sleeve and having its periphery in engagement with the shoulder, a lever secured at one end to the bearing sleeve and extending lengthwise of the adjacent offset portion, a can flange engaging driving wheel, a shaft carrying said wheel and extending through and rotatable in the sleeve, the driving wheel being movable with the sleeve relative to the

5 cutter, a crank connected with the shaft for rotating the same and the wheel, and means carried by the crank for engaging the lever upon rotation of the crank to impart turning movement to the lever, said last means being separable from the lever after a predetermined extent of rotation of the crank.

11. A can opener, comprising an elongated body, a knife connected with the body at one 10 end and having an offset parallel relation therewith, the body adjacent the knife end having a longitudinally extending slot therein, a bearing sleeve rotatable in said slot and movable lengthwise therein, a substantially U-shaped yoke partially enclosing the body and having two spaced 15 sides, each of said yoke sides being secured to the bearing sleeve to turn therewith, a link pivotally connected at one end with one of the sides of the yoke, a pivotal connection between the other end of the link and the body on a line lengthwise of the body with the rotary center of the sleeve, the first pivot for the link forming an elbow between the yoke and the body adapted to swing across said line, a lever connected with the other side of the yoke and extending lengthwise of the body, a shaft rotatable in the sleeve, a can flange engaging driving wheel carried by the shaft for movement with the yoke relative to the knife, a crank connected with the 20 shaft, and a shiftable element carried by the crank and adapted to have a predetermined period of connection with the lever upon rotation of the crank to oscillate the yoke and bend said elbow to effect the shifting of the sleeve and driving wheel relative to the knife.

12. A can opener, comprising an elongated body having a laterally offset upper end, a knife integral with said offset end and spaced from the body, the body adjacent the knife having a longitudinally extending slot therethrough, a sleeve 40 extending through and rotatable in the slot and movable lengthwise thereof, a resilient arm secured at one end and having an end extending across the plate beneath the sleeve, an eccentric wheel eccentrically secured to the sleeve at one 45 end and having its periphery in engagement with the second-mentioned end of the arm, a lever secured to the sleeve and extending lengthwise of the plate, a shaft rotatable in the sleeve, a can flange 50 engaging driving wheel carried by the shaft and movable with the sleeve relative to the knife, a crank connected with the shaft for rotation of the same, and an element carried by the crank and having limited lengthwise movement thereon and arranged for engagement with a side of the lever for a predetermined period of connection therewith during the rotation of the crank for effecting oscillation of the lever.

13. A can opener, comprising an elongated body having a laterally offset upper end, a knife integral with said offset end and spaced from the body, the body adjacent the knife having a longitudinally extending slot therethrough, a sleeve 55 extending through and rotatable in the slot and movable lengthwise thereof, a resilient arm secured at one end and having an end extending across the plate beneath the sleeve, an eccentric wheel eccentrically secured to the sleeve at one end and having its periphery in engagement with the second-mentioned end of the arm, a lever secured to the sleeve and extending lengthwise of the plate, a shaft rotatable in the sleeve, a can flange engaging driving wheel carried by the shaft and movable with the sleeve relative to the knife, a crank connected with the shaft for rota-

tion of the same, an element carried by the crank and having limited lengthwise movement thereon and arranged for engagement with a side of the lever for a predetermined period of connection therewith during the rotation of the crank for effecting oscillation of the lever, the said offset portion of the plate forming a head having two spaced walls, one of said walls being formed to provide said knife, and an idler wheel pivotally supported between said walls in the plane of the driving wheel for engagement with the said can flange.

14. A can opener, comprising an elongated body formed to provide an angular extension at one end, a shaft extending through the angular extension perpendicular thereto and supported for rotation, a cutting wheel upon one end of the shaft, the body having a longitudinally extending guide slot therein adjacent to said extension, a bearing sleeve extending through the guide slot for rotation therein and for movement lengthwise of the body, an eccentric wheel eccentrically supported upon the bearing sleeve and secured thereto for rotation therewith, a shaft extending through the bearing sleeve for rotation therein, a can flange engaging wheel secured to an end of the shaft upon the same side of the body as said cutting wheel for movement relative thereto, means providing a fulcrum with which the periphery of the eccentric wheel engages, a lever secured to the bearing sleeve to be turned therewith, a crank connected with the second-mentioned shaft to effect turning of the same and the driving wheel, and an element supported upon the crank for shifting movement lengthwise thereof and normally maintained in position to engage said lever upon rotation of the crank for imparting rotation to the bearing sleeve,

said element being movable out of connection with the lever after a predetermined extent of rotation of the crank.

15. A can opener, comprising an elongated body formed to provide an angular extension at one end, a shaft extending through the angular extension perpendicular thereto and supported for rotation, a cutting wheel upon one end of the shaft, the body having a longitudinally extending guide slot therein adjacent to said extension, a bearing sleeve extending through the guide slot for rotation therein and for movement lengthwise of the body, an eccentric wheel eccentrically supported upon the bearing sleeve and secured thereto for rotation therewith, a shaft extending through the bearing sleeve for rotation therein, a can flange engaging wheel secured to an end of the shaft upon the same side of the body as said cutting wheel for movement relative thereto, means providing a fulcrum with which the periphery of the eccentric wheel engages, a lever secured to the bearing sleeve to be turned therewith, a crank connected with the second-mentioned shaft to effect turning of the same and the driving wheel, and an element supported upon the crank for shifting movement lengthwise thereof and normally maintained in position to engage said lever upon rotation of the crank for imparting rotation to the bearing sleeve, said element being movable out of connection with the lever after a predetermined extent of rotation of the crank, said fulcrum means comprising a curved arm secured at one end to the body and having its other end free for resilient movement relative to the body, the periphery of the eccentric wheel being in engagement with the said other end.

ROBERT E. MCLEAN.
